UNITED STATES PATENT OFFICE.

GEORGE MAXIMILIAN ALEXANDER KOSTER, OF ECCLES, NEAR MANCHESTER,
ENGLAND.

SCOOTER.

1,394,430.

Specification of Letters Patent. Patented Oct. 18, 1921.

Application filed August 24, 1920. Serial No. 405,680.

To all whom it may concern:

Be it known that I, GEORGE MAXIMILIAN ALEXANDER KOSTER, subject of the King of Great Britain, residing in Eccles, near 5 Manchester, in the county of Lancaster and Kingdom of England, have invented certain new and useful Improvements in and Relating to Scooters, of which the following is a specification.

10 The object of the present invention is to provide a scooter specially adapted for propelling the rider forward on ice, snow or frozen roads or the like.

The scooter may be propelled by striking 15 on the ground with one foot, the boot of which may be provided with a spiked sole or a sole provided with other suitable gripping devices, or a detachable member may be provided for the boot, for instance a 20 spiked strap or equivalent; the spikes project underneath the sole and prevent the foot from slipping.

Runners may be used which may consist entirely of metal or of smooth surfaced 25 pieces of wood suitably shaped which may be provided with metal faces. Preferably the runners curve up sharply at the heel and gradually at the front or toe portion. The runners at the back may be connected to the 30 under side of the footboard in the form of a narrow continuous strip which curves backward from the back point of attachment, then downward, then sharply curves forward with a more or less horizontal—either 35 curved or straight—surface which curves upward and then back to be again attached to the footboard.

The invention is described by way of example with reference to the accompanying 40 drawings in which:—

Figure 1 is a side elevation, and
Fig. 2 is a plan.

In these drawings, 1 is a base which may be constructed of wood and (or) metal having an upstanding portion 2 to which is secured a pin 9 engaging within a bracket 10 secured by bolts 11 to the steering post 3 having a handle 4.

50 A back runner or runners 6 are secured to the base plate 1 by means of bolts 7 and a front runner 5 is secured to the bottom of the steering post by means of bolts 8.

It is preferred to have two parallel run-

ners at the back, say three quarters to one inch apart, but in some cases a single back 55 runner may be used. In the construction illustrated, a double bladed back runner is shown, and it will be noted also that the curves of the two blades are dissimilar, that is to say the points of contact 6 of the respective blades with the ice are not opposite 60 each other. This arrangement is designed to prevent skidding.

In the drawings it will be seen that the runners consist of thin strips which may be conveniently made of steel or other metal 65 adapted to engage the ice edgewise somewhat in the same manner as the blade of a skate. In the drawings, it will be seen that the end portions of the runners are twisted at right angles to the main portion so as 70 to enable these end portions to be screwed on or otherwise attached to the base plate 1 and the steering post 3. It is possible, however, to secure the strips without twisting the ends to 90° if the ends are inserted in 75 suitable slots within the base plate 1 and the steering post 3, but in this case the scouring bolts 7 and 8 will be at right angles to the position shown in the drawings. Clearly if desired a single sheet of steel or 80 other suitable material may be employed instead of a strip, and in this case the upper portion of the steel sheet may be secured within suitable slots as described.

I declare that what I claim is:—

An ice scooter comprising in combination 85 a platform, a steering head, a swivel connection between said platform and said steering head, a sheet metal runner arranged on edge mounted on said steering head, a pair of sheet metal runners arranged on edge mounted on said platform at an angle to one another so that their points of contact with the horizontal plane do not lie on a line inclined to the horizontal axis of 90 the scooter.

In witness whereof I have hereunto signed my name this 2nd day of August, 1920, in the presence of two subscribing witnesses.

GEORGE MAXIMILIAN ALEXANDER KOSTER.
